CLAIM

I claim the ornamental design for an infant care bag, as shown.

DESCRIPTION

FIG. 1 is a perspective view of my infant care bag design.

FIG. 2 is a top plan view of my infant care bag design. FIG. 3 is a plan view of one of the longer side of my infant care bag design, the opposite longer side being identical in construction and appearance.

FIG. 4 is a perspective view of my infant care bag design with the accordion fold safety card/first-aid folder removed from the folder storage pocket; and,

FIG. 5 is a plan view of one of the shorter side ends of my infant care bag design, the opposite shorter side end being identical in construction and appearance.

The rear of the fold safety card/first-aid folder not shown in FIG. 4 forms no part of the claimed design.
